(57) **CLAIM**

The ornamental design for a firearm as shown and described.

DESCRIPTION

FIG. 1 is a left side perspective view of a firearm showing our new design;

FIG. 2 is a front elevational view of the firearm of FIG. 1;
FIG. 3 is a rear elevational view of the firearm of FIG. 1;
FIG. 4 is a left side elevational view of the firearm of FIG.
1;

FIG. 5 is a right side elevational view of the firearm of FIG.
1;

FIG. 6 is a top plan view of the firearm of FIG. 1; and,
FIG. 7 is a bottom plan view of the firearm of FIG. 1.
The broken lines having consistent dash lengths (dash-dash-
dash) represent portions of the firearm that form no part of
the claimed design.

The broken lines having inconsistent dash lengths (long
dash-short dash-long dash) in FIGS. 1-6 represent bound-
aries of the claimed design.

1 Claim, 6 Drawing Sheets
